POCKET LIGHTING DEVICE

Filed June 18, 1927

THEODOR SCHILD
INVENTOR:

Otto Klemm
ATTORNEY

UNITED STATES PATENT OFFICE

THEODOR SCHILD, OF GRENCHEM, SWITZERLAND

POCKET LIGHTING DEVICE

Application filed June 18, 1927, Serial No. 199,712, and in Switzerland April 6, 1927.

The present invention relates to a new and improved device for lighting pipes, cigars, etc. and more especially to a device adapted to be carried in the pocket and comprising 5 a container containing material soaked in gasoline or equivalent spirit and feeding a wick, a piece of pyrophorous metal arranged in proximity to said wick and a rotary scraper with abrasive surface frictionally engaging said piece of pyrophorous metal in such a manner that by turning said scraper sparks are produced serving to ignite the gasoline ascending by said wick.

The main object of the invention is to provide a device of the said class which allows an easy and rapid cleaning and inspection.

Another object of the invention is to provide an improved device which shall be simple, strong and durable in construction and 20 efficient in use.

Other objects of the invention relate to the provision of minor parts and to details of construction all of which will be more clearly set forth in the following specification.

I attain these objects by placing the pyrophorous metal piece together with a spring pressing the same on to the abrasive surface of the rotary scraper disc into a casing rotatably arranged on the axis of rotation of said 25 scraper disk in such a manner that the casing may be made easily accessible by swinging it out of the container in which it is normally placed.

In the accompanying drawings forming 30 part of the specification a preferred mode of construction is shown by way of an example.

Fig. 1 shows the top portion of a pocket lighting device in sectional elevation,

Fig. 2 is a top view, the lid of the device 40 being removed,

Fig. 3 is a cross-section on line III—III of Fig. 2.

In the drawing 1 denotes a container with a compartment 5 in which a material soaked 45 with gasoline, petrol or equivalent spirit is stored. The container 1 is moreover provided with a lid 2 hingedly connected to said container 1 at 3. In the chamber formed by the top wall 4 and by the lid 2 a tubular casing 9 is rotatably arranged. A cylindrical

stud 13 projects through a cross bore of said casing 9. The stud 13 forms part of a piece 12 rigidly connected to the wall 4. A screw 11 with a large head screwed into said stud 13 secures the casing 9 against axial displacement. On the stud 13 a round disk 6 of hardened steel or the like is rotatably mounted. The surface of the disk 6 is roughened to form a scraper. A piece 7 of pyrophorous metal placed in said casing 9 is pressed 60 against the roughened surface of the disk 6 by means of a coiled spring 8 abutting against a set screw 10 screwed into the free end of casing 9. The casing 9 rests on a support 15 fastened to the wall 4, the support 15 is 65 provided with a shallow groove engaged by the casing 9, the latter being secured thereby against accidental displacement. In close proximity to the disk 6 and piece 7 a wick 14 is arranged in the well known manner. By turning the disk 6 sharply a gerb of sparks is produced which are thrown on to the wick 14 igniting the vapour ascending therefrom.

To inspect, to clean and to adjust the igniting device proper and to refill the casing 9 the latter is turned into the position shown in dotted lines (Fig. 2).

The support 15 may be replaced by a snap fastener or any other device retaining the 80 casing 9 in its working position.

It will be obvious that changes of details may be made within the true scope of the invention which is set forth in the claims.

What I claim and wish to secure by U. S. 85 Letters Patent is:

1. A pocket lighting device, comprising a flat container substantially rectangular in cross section and having a horizontal supporting wall adjacent one of its ends, a vertical stud fixed in said wall, a tubular casing rotatable in a horizontal plane about said stud parallel to said supporting wall, a friction wheel also rotatable about said stud and partly enclosed in said tubular casing, and a spring pressed pyrophoric element in said casing and adapted to adjustably engage said friction wheel. 90

2. A pocket lighting device, comprising 95

100

the combination with the elements claimed in
claim 1, of a grooved block mounted on said
supporting wall at a point remote from said
stud and adapted to receive the end of the tu-
5 bular casing remote from said stud.

5 In witness whereof I affix my signature.

THEODOR SCHILD.
